CARPET.

No. 15,541.

Patented Nov. 11, 1884.

UNITED STATES PATENT OFFICE.

JAMES LYALL, OF NEW YORK, N. Y., ASSIGNOR TO THE CHELSEA JUTE MILLS, OF SAME PLACE.

DESIGN FOR A CARPET.

SPECIFICATION forming part of Design No. 15,541, dated November 11, 1884.

Application filed June 27, 1884. Term of patent 7 years.

To all whom it may concern:

Be it known that I, JAMES LYALL, of the city and State of New York, have invented a Design for Carpets, of which the following is 5 a specification.

This design is for a carpet, and is shown in the annexed photograph.

The design consists of checks of different appearance placed alternately. In each check B to there are lines of diagonal ridges a, and in each check C there are zigzag lines, producing a diagonally-mottled appearance, all as shown.

I claim—

The design for a carpet, composed of the alternate checks, having the appearance described and shown in the photograph.

Signed by me this 24th day of June, A. D. 1884.

JAMES LYALL.
